DESIGN FOR A FRONT FOR AN ILLUMINABLE MIRROR CABINET

Carl A. Laystrom, Decatur, and Howard R. Sigler,
Argenta, Ill., assignors, by mesne assignments,
to Faries Manufacturing Company, Chicago,
Ill., a corporation of Illinois

Application March 18, 1948, Serial No. 145,196

Term of patent 14 years

(Cl. D4—3)

To all whom it may concern:

Be it known that we, Carl A. Laystrom and Howard R. Sigler, both citizens of the United States, and residents of the city of Decatur, in the county of Macon and State of Illinois, and of the city of Argenta, in the county of Macon and State of Illinois, respectively, have jointly invented a new, original, and ornamental Design for a Front for an Illuminable Mirror Cabinet, of which the following is a specification, reference being had to the accompanying drawing, forming a part thereof.

On the drawing:

Figure 1 is a front elevational view of a front

for an illuminable mirror cabinet, showing our new design;

Figure 2 is a top plan view thereof; and
Figure 3 is a side elevational view thereof.

We claim:

The ornamental design for a front for an illuminable mirror cabinet, as shown.

CARL A. LAYSTROM.
HOWARD R. SIGLER.
